CHARLES ORME BASTIAN, OF LONDON, ENGLAND, ASSIGNOR TO COOPER HEWITT ELECTRIC COMPANY, OF HOBOKEN, NEW JERSEY, A CORPORATION OF NEW JERSEY.

VAPOR ELECTRIC APPARATUS.

1,122,185.

Specification of Letters Patent. Patented Dec. 22, 1914.

Original application filed December 9, 1905, Serial No. 292,480. Divided and this application filed December 5, 1913. Serial No. 804,817.

To all whom it may concern:

Be it known that I, CHARLES ORME BASTIAN, a subject of the King of Great Britain, and resident of 75 Brondesbury road, London, England, have invented certain new and useful Improvements in Vapor Electric Apparatus, of which the following is a specification.

This invention relates to vapor electric apparatus, especially electric lamps.

The lamp consists of a tube containing a vaporizable material such as mercury for forming the electrodes and the entire lamp is, according to present custom, called a "burner," and this irrespective of whether the apparatus be used for giving light or for other purposes, such as rectifying or rupturing electric circuits.

It has been proposed to start mercury vapor apparatus by means of a shunt electro-magnet, and to leave the latter in circuit during subsequent operation, but I find it desirable to arrange for the pressure within the arc to automatically cut out of circuit the shunt electro-magnet during such time as the lamp is in operation and to restore the connection when the current is switched off and the pressure subsides through cooling, and I may conveniently effect this by causing the pressure to act on a body of mercury behind the positive electrode as aforesaid for example by separating the electro-magnet circuit connection from the positive electrode.

My invention is illustrated in the accompanying drawing which shows a burner adapted to carry out the purposes of my invention.

In the drawing an enlargement b^1 is shown at the electrode b and also an enlargement c^1 at the positive electrode c while the bulb d (for receiving that part of the

mercury which is displaced from the arc path in the tube a) is located outside the path of the arc stream between the electrodes c and b ; and furthermore, between said positive electrode c and said bulb d I may provide a subsidiary positive electrode j which is in circuit with the electro-magnet which is employed to start the lamp by 45 tilting or said subsidiary positive electrode j may be connected in any other circuit (such as a resistance circuit) which it may be desired to cut out after the burner has been started.

In operation the mercury which before the lamp is started will normally connect the electrodes b and c will be removed from the tube a beyond the surface of the electrode c and will ultimately be removed back 50 clear of the surface of the subsidiary electrode j whereby circuit through the latter will automatically be broken.

In the following claim the terms "burner" and "mercury" are (for the sake of brevity) 55 respectively used to denote and include any suitable device and any suitable electrode material as hereinbefore defined or explained.

I claim as my invention:

In a burner for electric apparatus, a container, main electrodes of mercury therein, a subsidiary contact therein located outside the path between the main electrodes, but within the limits of the movement of the mercury in normal operation of the 70 burner, whereby the said subsidiary contact is cut out of the circuit.

Signed at London in the county of London and England this 18th day of November A. D. 1913.

C. ORME BASTIAN.
